S. T. THOMAS & E. EVERETT.

E. A. EVERETT, Administratrix of E. EVERETT, Dec'd.

WARPING AND DRESSING YARN.

No. 11,436.

Patented Aug. 1, 1854.

UNITED STATES PATENT OFFICE.

SAMUEL T. THOMAS AND ELIZA ANN EVERETT, OF LAWRENCE, MASSACHUSETTS; SAID ELIZA ANN EVERETT ADMINISTRATRIX OF EDWARD EVERETT, DECEASED.

WARPING AND DRESSING YARNS.

Specification of Letters Patent No. 11,436, dated August 1, 1854.

To all whom it may concern:

Be it known that I, SAMUEL T. THOMAS, of Lawrence, in the county of Essex and State of Massachusetts, in conjunction with Edward Everett, deceased, late of said Lawrence, have invented certain new and useful Improvements in the Mechanical Process of Warping and Dressing Yarns, and that the following description, taken in connection with the accompanying drawings, hereinafter referred to, forms a full and exact specification of the same, wherein are set forth the nature and principles of our said improvements, by which our invention may be distinguished from others of a similar class, together with such parts as are claimed, and desired, to be secured by Letters Patent.

The figures of the accompanying plate of drawings represent my improvements.

In plate 1, Figure 1 is a plan or top view of my machine, and Fig. 2 an enlarged central vertical section of the sectional loom beam. Fig. 3 is a plan of the entire loom beam. In Plate 2, Fig. 4 is a side elevation of the machine and Fig. 5 an enlarged vertical section of one of the fan cylinders.

The ordinary method of warping and dressing cotton yarns, is by the agency of the distinct machines. First, a machine called a warper, in which 200 or 300 small spools or bobbins of yarn are placed, that deliver the yarns to a beam four or five feet long, with heads of about fifteen inches diameter, technically called a "section beam." As the yarns are wound upon these beams, they frequently increase in diameter faster at one end, than at the other, and as some of the yarns are taken onto the beam faster than others, a general unevenness is produced upon the surface of the beam. Secondly, eight of said section beams are placed in a machine, (four at each end) called a dresser. To each beam a friction strap, lever, and adjustable weight is applied. In the center of said dresser, is placed a loom beam, driven by necessary gearing. The yarns from the several section beams, are passed through proper guides, or raddles; thence through four or eight sets (as the operator may decide), of size rolls, thence through other raddles, brushes, &c., to the center of the machine, where they are attached to the loom beam. Motion is then given to the loom beam, caus-

ing all the size rolls, and the eight section beams, to revolve by the tension or draft of the yarns.

The purpose of the strap, lever, and adjustable weight is, to prevent the section beam from revolving too easily; and to produce sufficient resistance, to take the elasticity from the shorter threads, or cause them to stretch sufficiently to keep the longest ones straight.

The weights are adjusted by the tender, as the section beams decrease in diameter, in order to equalize the tension of the yarns. The uniformity of tension, which is very important, is thus dependent upon the care and judgment of the tender.

Our improvements consist first, in warping, and dressing, directly from small spools, or bobbins, to sectional loom beams, which as fast as completed, are arranged side by side, on a shaft, and then placed in the loom. By this method of warping, and dressing, the varying tension of the yarns, is avoided; as the spools, or bobbins, which supply the yarns, are light and of small diameter, and being independent of each other, and readily inserted, or removed, afford greater facilities, in the arrangement of colors, and in making up, and changing an unlimited variety of stripes, in the warp yarns, and consequently in the fabric.

The amount of tension on the yarns, running from these small bobbins, is not sufficient to take any of the elasticity from the yarns, being only enough to keep them straight, so that one thread shall not twist around another, previous to their entering between the size rolls. After passing between the size rolls, there is no variation in the tension, but each individual thread will bear its equal proportion of strain, whereby the elasticity will be taken alike, from each of the threads, which will be delivered upon the loom beam in like manner.

The amount of strain, or tension, given to the threads, previous to their entering between the size rolls, is not more than five per cent of the amount given them, when they are delivered upon the loom beam.

The amount of varying tension, the threads receive, in turning the small bobbins by the variation of their diameters, while the yarn is being unwound, is so slight, that it is not perceptible in the work.

It will readily be seen that yarn sized,

and dressed, and delivered, upon a loom beam ready for weaving, with the stretch, or elasticity, taken from each of the threads alike, will weave with very much less breaking, than those yarns, which, as by the old process have been dressed and delivered, to the loom beam, with nearly all the elasticity taken from them, while the others have not been stretched at all.

10 In our machine fewer yarns are drawn through, as only one section, or part of the loom beam, is formed at once, whereby a large number of sizing rolls, may be dispensed with, which have heretofore been used, and, which still further increase the variation of tension in the yarns which pass between them.

15 In our machine, by warping and dressing directly from small bobbins, or spools, containing each but one thread, they are so readily inserted, or removed, that great facilities for the arrangement of colors, are afforded, while the width of the loom beam, and the number of threads to the inch, can 20 be varied at pleasure, and is not, as in the old method, dependent upon the width and number of threads, contained on the section beam. The stripes, in the fabric, can also be varied by this arrangement, at will, without changing the spools, or bobbins, which supply the yarns. This is done, by so placing the sectional loom beams, with regard to each other, in the loom, as to bring the end stripe of one, immediately adjacent to 25 a similar stripe of the next, it being only necessary, in thus arranging the sectional loom beams, to alternate their direction of revolution, while being filled, as will hereinafter be more fully explained.

30 40 We have also made an essential improvement in the method of drying yarns, after they have passed through the sizing trough. The fans which hitherto have been employed for this purpose, have but imperfectly performed their office, as they blow the air against the yarns in a single current or jet, and therefore but a small portion of the 35 yarns, lie in the current of air at a time, while the force of the current thus impinged against the yarns, blows them so far away when broken, as to prevent their being readily reunited. In our improved machine, the 40 yarns pass around an open slatted cylinder within which, the fans are revolved at a rapid rate. By this arrangement the current produced by the revolution of the fans, is directed in a gentle breeze to a large portion or surface of the yarns which extend around the cylinder, the force of the current being 45 broken by the slats of the same.

50 a a a in the drawings represent the supporting framework of the machine.

55 b, b, are the spools or bobbins upon which the yarns are wound. These spools are of small diameter, and are arranged as shown

in Fig. 1 Plate 1, and Fig. 4 Plate 2. The 60 yarns, represented by colored lines in the drawings, pass from these spools, through proper saddles or guide c c, between the sizing rolls d, d, and from thence through saddles e, e, and over the roll f, as shown in Fig. 1 Plate 1, and Fig. 4 Plate 2, to the first slatted fan cylinder g g, the construction and operation of which will now be described.

65 h h &c., Fig. 5 Plate 2, are the fans connected by proper arms i i, to a revolving shaft k. These fans revolve in, and are encased by a cylinder composed of slats g, g arranged with spaces or openings between them. The journals of this cylinder rest upon friction rolls l, l, shown by dotted lines in Fig. 4, so as to be easily revolved by the drawing of the yarns, which are guided by the roll f, before referred to, and the first heating cylinder m, around a large portion of the periphery of the slatted fan cylinder g g. By this arrangement, the yarns, instead of being exposed to a strong single current or jet of air upon a small portion of their length only, as occurs in the use of the ordinary fan, the construction of which is well known, are kept, as it were, in a gentle circulation or current of air, the force of the current, produced by the revolution of the fans, being broken by the slats g, g, between which the air has to pass before reaching the yarns. As the yarns are made to pass around a large portion of the periphery of the slatted cylinder g g, they are exposed, through a large portion of their length, to the current of air produced by the fans, thus facilitating the process of drying, while in the case of the breaking of a yarn, it can be readily reunited, as it 70 is not blown off, which often happens in the use of the common fans for drying yarns. After passing around the first slatted cylinder g g, and over the first heated metallic cylinder m, the yarns pass under the heated cylinder n, and over the heated cylinder o, to the second slatted fan cylinder p p, constructed in a precisely similar manner to the slatted cylinder g g, and from thence over the roll q q, and through the saddles r r. From these saddles r r they converge to the last saddles s s, through which they pass and are wound upon a sectional loom beam t, as shown in the drawings; but as we intend to make the construction and arrangement of the sectional loom beams form the subject of a separate application for a patent, the manner of making up an entire loom beam from the sectional loom beams need not now be more fully explained.

75 80 85 90 95 100 105 110 115 120 125 130 It will readily be seen, that in order to facilitate the drying process, the slatted fan cylinders may be supplied with hot air, so as to keep the yarns in a heated current while passing around them, and the yarns,

after passing through the sizing apparatus, may be dressed in the usual manner by brushes.

Having thus described our improvements 5 our claims will be stated as follows:

What is claimed as our invention and desired to be secured by Letters Patent is—

1. The above described improvements in the process of warping, and dressing yarns, 10 consisting, first, in warping and dressing yarns, directly from small spools, or bobbins, instead of from large section beams heretofore used, to sectional loom beams, for the purpose of securing a uniform tension 15 in the yarns wound upon the loom beam, and also affording greater facilities for readily producing a variety in the stripe of the fabric, as hereinabove set forth.

2. Our improvement in the fan cylinder for drying the yarns, which consists in a 20 cylinder composed of slats, arranged with spaces between them, and around which slats, the yarns are made to pass, revolving fans being arranged within the said cylinder, and revolving independently of, and at 25 a much more rapid rate, than said slatted cylinders, whereby a large portion of the yarns are kept in a gentle current of air, and rapidly dried as above described.

SAML. T. THOMAS.
